INVENTOR

Frank Shay,

BY

Charles H. Bell.

ATTORNEY.

UNITED STATES PATENT OFFICE.

FRANK SHAY, OF NEWARK, NEW JERSEY.

COMBINED CLEAN-OUT, BACKWATER-TRAP, AND CELLAR-DRAIN.

SPECIFICATION forming part of Letters Patent No 772,583, dated October 18, 1904.

Application filed June 15, 1904. Serial No. 212,620. (No model.)

To all whom it may concern:

Be it known that I, FRANK SHAY, a citizen of the United States, residing at Newark, in the county of Essex and State of New Jersey, have invented certain new and useful Improvements in a Combined Clean-Out, Backwater-Trap, and Cellar-Drain; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 The general object of this invention is to provide a clean-out for drain-pipes which shall also permit the inflow of water to said drain and yet prevent backing up or outflow from the drain-pipe.

20 More particular objects of the invention are to enable the valve means in the said device to be temporarily removed out of the way and provide an unobstructed passage for cleaning out the drain, to at the same time preserve a permanent attachment of said valve means, and to secure other advantages and results, some of which may be hereinafter referred to in connection with the description of the working parts.

25 The invention consists in the improved combination clean-out, cellar-drain, and backwater-trap and in the arrangements and combinations of parts of the same, all substantially as will be hereinafter set forth, and finally embraced in the clauses of the claim.

Referring to the accompanying drawings, in which like figures of reference indicate corresponding parts in each of the several figures, Figure 1 is a vertical central section of my improved device. Fig. 2 is an underneath view with the valve in operative position, and Fig. 3 is a view from below with the valve-ball removed and its retaining means swung to one side to present an unobstructed passage.

In said drawings, 2 indicates a cylindrical ferrule adapted to be seated in the end of a drain-pipe and packed therein with oakum and lead, as is common in the art, to secure an impervious fit. The upper end of said fer-

rule is interiorly threaded, as at 3, to receive a cap 4, perforated, as at 5, to permit the drainage of water and having a central angular boss 6 to receive a wrench. It will be understood that said perforated cap 4 is adapted when my device is in final position to lie flush with the surface to be drained and close the end of the drain-pipe.

At the under side of the cap 4 is a funnel-like or conical extension 7, preferably formed of sheet metal and arranged with its upper edge within the threaded flange 8 of the cap. Said extension 7 may be attached to the cap 4 in any suitable manner and either permanently or removably, as desired. At the lower end of the extension 7 its edges are curled outward, as at 9, to form a circular seat for a valve-ball 10. Said ball 10 may be of any construction desired, although I have shown it formed of an interior body portion 11 of cork, with a cover 12 of rubber.

It will be understood that in operation the ball 10 is raised by floating against the end 9 of the extension 7 to prevent backflow of water out of the drain, and therefore means must be provided to support the ball in idle position, and at the same time said means must be movable to enable the device to perform its function of serving as a clean-out. To this end I have arranged in the lower end of the ferrule 2 a ball-support hinged to the ferrule and adapted to fold or swing against the sides of the said ferrule.

I have shown a construction consisting of two wires 13, each bent into hemispherical shape and having its ends 14 bent outwardly apart into the same straight line and adapted to enter perforations 15 in the walls of the ferrule. These two wires are arranged diametrically at right angles to each other, and one is provided with a notch or recess 16, into which the other may be snapped when the said wires are in position. Therefore, as shown in Figs. 1 and 2, the ball is securely supported; but when the cap 4 and ball 10 are removed for purposes of cleaning out the drain then the said wires 13 can be swung against the sides of the ferrule, as shown in Fig. 3, to provide an unobstructed passage into the drain-pipe.

Obviously other means of hinging the ball-support than those specifically set forth may be provided without departing from the spirit and scope of the invention, the purpose of 5 which is to provide a ball-support which shall not be separable or detachable from the ferrule, but still adapted to move out of the direct passage-way. I do not, therefore, wish to limit myself by the positive descriptive 10 terms herein employed except as the state of the art may require.

Having thus described the invention, what I claim as new is—

1. The combination with the ferrule 2, having a cap at its upper end providing an interior downwardly-facing valve-seat, of a ball-valve, and a support beneath said ball hinged to the ferrule.
2. The combination with the ferrule having 20 at its upper end a cap providing an interior downwardly-facing valve-seat, of a float-valve beneath said valve-seat and a support adapted to hold said ball in idle position and being hinged to the walls of the ferrule to fold there- 25 against.
3. The combination with the ferrule having at its upper end a cap providing an interior downwardly-facing valve-seat, of a float-valve,

and a valve-support comprising a plurality of parts each hinged to the ferrule and adapted 30 to fold thereagainst or to be extended into transverse engagement with the other of said parts.

4. The combination with the ferrule having at its upper end a cap providing an interior 35 downwardly-facing valve-seat, of a float-valve, and a valve-support comprising bent wires arranged diametrically of the ferrule and having their ends journaled in perforations in the walls thereof.

5. The combination with the ferrule having at its upper end a cap providing an interior 40 downwardly-facing valve-seat, of a float-valve, and a valve-support comprising bent wires arranged diametrically of the ferrule and having 45 their ends journaled in perforations in the walls thereof, one of said wires being notched to receive another in final position.

In testimony that I claim the foregoing I have hereunto set my hand this 13th day of 50 June, 1904.

FRANK SHAY.
